UNITED STATES PATENT OFFICE

141,563

DESIGN FOR A SPECTACLE FRAME OR SIMILAR ARTICLE

Arthur Blum, Brooklyn, N. Y.

Application October 16, 1944, Serial No. 115,817

Term of patent 14 years

(Cl. D57—1)

To all whom it may concern:

Be it known that I, Arthur Blum, a citizen of the United States and a resident of Brooklyn, New York, in the State of New York, have invented a new, original, and ornamental Design for a Spectacle Frame or Similar Article, of which the following is a specification, reference being had to the accompanying drawing, forming a part thereof, in which

Figure 1 is a front elevational view of a spectacle frame or similar article, showing my new design; and

Fig. 2 is a top plan view thereof.

My design for a spectacle frame of the specific form as illustrated on the drawing is characterized by the thick heavy boldness of all parts of the frame, wherein the center of the high temple mounts is in substantial alignment with the center of the nose bridge and the four sides of the lens rims are substantially straight having but a very slight curvature.

I claim:

The ornamental design for a spectacle frame or similar article, as shown and described.

ARTHUR BLUM.
